UNITED STATES PATENT OFFICE.

JOSE DELGADO Y AGUILAR, OF NEW YORK, N. Y.

FIRE-ESCAPE.

SPECIFICATION forming part of Letters Patent No. 629,228, dated July 18, 1899.

Application filed May 9, 1899. Serial No. 716,119. (No model.)

To all whom it may concern:

Be it known that I, JOSE DELGADO Y AGUILAR, of the city of New York, borough of Brooklyn, in the county of Kings and State of New York, have invented a new and Improved Fire-Escape, of which the following is a full, clear, and exact description.

The object of my invention is to construct a strong and economic device adapted for permanent attachment within a building or at the outside thereof which will provide means of escape from fires in buildings of any height or number of floors and with the greatest possible rapidity and safety.

Another object of the invention is to construct a fire-escape so simple in operation that the most excitable person can successfully make use of it.

The invention consists in the novel construction and combination of the several parts, as will be hereinafter fully set forth, and pointed out in the claim.

Reference is to be had to the accompanying drawings, forming a part of this specification, in which similar characters of reference indicate corresponding parts in all the figures.

Figure 1 is a partial sectional perspective view of a building, illustrating the improved fire-escape applied to both the inside and the outside of the building. Fig. 2 is a front elevation of the improved fire-escape, drawn on an enlarged scale; and Fig. 3 is a side elevation thereof.

When the fire-escape is to be applied to the outside of the building, a bracket A is secured upon the roof of said building, which bracket projects beyond the cornice. A spindle 10 is mounted to slide in the outer end of the bracket A, said spindle being attached below the bracket to the frame 11 of a peripherally-grooved pulley 12. The spindle 10 is provided with a head 10^a, and a spring 13 is coiled around the spindle, having bearing upon the bracket A and against the said head 10^a. A hanger 14 is secured to the under surface of the lowest floor C of the building. This hanger is provided with a downwardly-extending arm 15 and a horizontal fixed shaft 16, upon which shaft 16 a peripherally-grooved pulley 17 is mounted to turn, the pulley 17 being in vertical alinement with the upper pulley 12.

A gear 18 is secured to the back of the pulley 17, and this gear meshes with a pinion 19, secured on a shaft 20, which shaft is mounted 55 to revolve in the hanger 14 and its arm 15, as is best shown in Fig. 2. The shaft 20 extends beyond the arm 15, and a blade 21 is attached to the projecting portion of said shaft. An endless chain or cable 22 is passed 60 around both pulleys 12 and 17, the cable or chain being held under perfect tension at all times by the spring 13 on the support for the upper pulley 12. The inner stretch of the chain or cable 22 is made to pass through a 65 tube 23, which tube is secured by screw-eyes 24 or their equivalents to the surface near which the escape is erected, and the object of the tube 23 is to prevent persons grasping the inner stretch of the rope, compelling them to 70 take the outer stretch, so that by no possibility can persons use the escape in such manner that the weight of one would practically counterbalance the weight of the other, thus preventing the descent of either to the ground. 75

When a person grasps the outer stretch of the cable 22, the cable will turn quickly on the pulleys 12 and 17, and the rapidity of the descent will be controlled by the blade 21, which will be revolved as the person descends, 80 said blade thereby serving as a retarding device.

When the escape is to be erected within a building, a fireproof shaft 25 is erected, extending from the bottom to the top floor, and 85 the upper portion of the escape is secured to the ceiling of the uppermost apartment within the said shaft. This fireproof shaft 25 at each floor except the bottom floor is provided with a window 26 at one side and a door 27 opposite to the window, the doors 27 opening outward, and these doors are provided with spring-hinges that will close immediately upon a person entering the shaft, thus preventing flames from gaining access to the interior of the shaft. At the bottom floor a door 28 is located in the shaft, opening outward to facilitate the ready exit of any person descending by the fire-escape. 95

Having thus described my invention, I claim as new and desire to secure by Letters Patent—

The herein-described fire-escape consisting of an upper support, a spindle fitted to slide

in said support and provided with a head above the same, a spring coiled around said spindle and bearing against the support and head, a pulley-frame carrying a pulley and secured to the spindle below the support, a hanger below the support and having a fixed shaft secured therein and a downwardly-extending arm, a pulley mounted on said shaft, being connected with the first-named pulley

and having a gear-wheel secured thereto, and a rotary shaft fitted in the hanger and its arm and carrying a pinion at one end meshing with said gear-wheel and a blade at its other end, as set forth.

JOSE DELGADO Y AGUILAR.
